US0D1059399S

(12) **United States Design Patent** (10) Patent No.: **US D1,059,399 S**
Chen et al. (45) Date of Patent: ** Jan. 28, 2025

(54) **DISPLAY SCREEN OR PORTION THEREOF WITH GRAPHICAL USER INTERFACE**

(71) Applicant: **Apple Inc.**, Cupertino, CA (US)

(72) Inventors: **Kevin Will Chen**, Cupertino, CA (US); **Teofila Connor**, San Francisco, CA (US); **Alan C. Dye**, San Francisco, CA (US); **Aurelio Guzmán**, San Jose, CA (US); **Vincenzo Vuono**, Sunnyvale, CA (US); **Christopher I. Wilson**, San Francisco, CA (US)

(73) Assignee: **Apple Inc.**, Cupertino, CA (US)

(**) Term: **15 Years**

(21) Appl. No.: **29/940,791**

(22) Filed: **May 6, 2024**

Related U.S. Application Data

(63) Continuation of application No. 29/900,389, filed on Aug. 21, 2023, now Pat. No. Des. 1,032,642, which is a continuation of application No. 29/890,454, filed on Apr. 24, 2023, now Pat. No. Des. 1,001,150, which is a continuation of application No. 29/861,957, filed on Dec. 5, 2022, now Pat. No. Des. 989,108, and a continuation of application No. 29/861,959, filed on Dec. 5, 2022, now Pat. No. Des. 988,347, said application No. 29/861,957 is a continuation of application No. 29/844,160, filed on Jun. 27, 2022, now Pat. No. Des. 971,946, said application No. 29/861,959 is a continuation of application No. 29/844,160, filed on Jun. 27, 2022, now Pat. No. Des. 971,946, which is a continuation of application No. 29/832,467, filed on Mar. 28, 2022, now Pat. No. Des. 956,079, which is a continuation of application No. 29/750,459, filed on Sep. 14, 2020, now Pat. No. Des. 949,169.
